Attorney

UNITED STATES PATENT OFFICE.

ARTHUR C. HOPKINS, OF MINNEAPOLIS, MINNESOTA, ASSIGNOR TO MID-WEST MANUFACTURING COMPANY, OF MINNEAPOLIS, MINNESOTA.

COMMUTATOR.

1,311,894.

Specification of Letters Patent. Patented Aug. 5, 1919.

Application filed January 17, 1919. Serial No. 271,620.

To all whom it may concern:

Be it known that I, ARTHUR C. HOPKINS, a citizen of the United States, residing at Minneapolis, in the county of Hennepin and State of Minnesota, have invented certain new and useful Improvements in Commutators, of which the following is a specification.

This invention relates to improvements in commutators for use more particularly in connection with the Ford engine, and has for its objects to provide an improved commutator which will be accurate in action, capable of convenient control and ready adjustment, and less subjected to wear as compared with other commutators.

The invention has reference to the use of few and simple parts which, however, will be effective in operation for the purpose required. Other objects of the invention will be stated hereinafter.

The invention consists of the novel construction, combination and arrangement of parts as described herein and claimed, and as illustrated in the accompanying drawing, wherein:

Figure 1 is a view in longitudinal section of a commutator embodying my invention, parts being broken away. Fig. 2 is a bottom plan view of the casing. Fig. 3 is a plan view of the casing. Fig. 4 is a face view of a part of the wall of the engine to show an annular groove. Fig. 5 is a side view of the movable, electrical contact-pin or plunger. Fig. 6 is a bottom plan view of a cap employed for the mounting of a cam upon the cam shaft. Fig. 7 is a plan view of a cam.

Referring now to the drawing for a more particular description, the invention is illustrated in connection with the wall 8 and the conventional cam shaft 9 of an internal combustion engine, said wall being provided with an annular groove 10 circumscribing and equidistant from the aperture 11 formed in said wall. At 12 is indicated a casing preferably having the form of a truncated cone, adapted to be seated in the groove 10, said casing being provided at its convergent end with a longitudinally apertured, cylindrical insulating block 13 which, preferably projects inwardly of said casing as clearly shown in Fig. 1, the casing also being provided at one of its sides with an apertured bracket 14 for receiving

the end of a pull-rod 15. The cylindrical insulating block 13 is provided centrally with an upset projection *a* having a concaved depression *b* formed therein to open on its upper end.

As thus described the depression *b* is disposed in line with the cam-shaft 9, and in order that the casing 12 may be maintained in the groove 10 and may be held therein without undue vibration I provide a flat spring 16, one of its ends being mounted upon the conventional oil well 17 formed generally on the type of automobiles first mentioned, its opposite end being provided with a convexed projection 18 adapted to be seated in the depression *b* of the insulating block, and it will be appreciated that the pressure upon all parts of the divergent end of the casing within the groove 10 will be uniform, this being an important feature for correct tuning in the operation of the commutator, the resiliency of the spring 16 being adequate for the purpose mentioned and adapted to overcome the resistance of another part hereinafter to be mentioned.

Upon the shaft 9 is mounted a cam 19 provided with a recess 20 for receiving the electrical contact-pin or plunger 21 and a spring 22, the latter normally causing a pressure of the pin against the inner face of the cylindrical insulating block 13, and mounted in the apertures of said block are electrical contact pins 23 each being provided with an electrical conductor 24 connected to the primary of a coil (not shown); the engine, the shaft 9 and plunger 21 operating as a part of the electrical circuit, as usual. Numeral 25 indicates an apertured cap adapted to be threaded upon the cam for use in combination with the nut 26 for securing the cam upon the shaft 9.

It will be understood that the cam shaft 9 is revolved by operation of the engine, and that the contact-pins 23 are disposed in the cycle of movement of the plunger 21 and that electric circuits will be complete when the plunger makes contact with the pins 23 for conducting electrical charges to the hydrocarbon mixtures, this being well known and requiring no particular description, the function discharged by the rod 15 and bracket 14 being to adjust the casing 13 circularly so that the electrical sparks acting on the hydrocarbon mixture for causing ignition thereof may be under control.

Among some of the advantages to be derived by the present construction it may be stated that all of the functions required for a commutator are discharged by a more simple construction than usual and manufacture will be attended with a correspondingly less expense; since the plunger 21 is disposed parallel with the axis of the shaft 9 the pressure of the plunger against the face of the block 9 and the ends of the metallic pins 23 will not be materially affected by centrifugal force. It will be understood that the spring 16 is depended upon for holding the casing 12 upon its seat within the groove 10 against the force of the spring 22 and operation of friction of the plunger against the inner face of the insulating block, and the fact that all of the force of the spring 16 is applied in line with the axis of the rotatable shaft 9, by means of the concaved depression *b* and the convexed projection 18 of the spring 16, tends to prevent vibration of the casing 12, and also permits an adjustment of more than usual accuracy when the rod 15 is used, these being important features in operation.

What I claim as new and desire to secure by Letters Patent is:—

In a commutator, the combination with a cam shaft, of a wall having a bearing supporting one end of the cam shaft and 30 having a groove made in one face of the wall with a shoulder at the outer periphery of the groove and an inclined surface at the inner periphery of the groove, a frusto-conical casing having its base seated in said 35 groove and lying inside said shoulder, means whereby the casing may be turned in said groove, an insulating block fastened in the top of said casing, contact pins carried by said block, a cam turning with said cam 40 shaft having a recess, a headed contact plunger fitted loosely in said recess and arranged to move over the first-named pins, a spring in the recess beneath the headed 45 plunger, a projection on the block having a depression, and a flat spring having a convex knob resting in said depression and serving to yieldingly hold the casing in the groove while allowing the same to be turned.

In testimony whereof I have affixed my 50 signature in presence of two witnesses.

ARTHUR C. HOPKINS.
